UNITED STATES PATENT OFFICE.

HARRY W. BOLENS, GEORGE T. STRITE, AND CHARLES J. TRAVERS, OF PORT WASHINGTON, WISCONSIN, ASSIGNEES OF ONE-THIRD TO SAID BOLENS, ONE-THIRD TO SAID STRITE, AND ONE-THIRD TO SAID TRAVERS, ALL OF PORT WASHINGTON, WISCONSIN.

HOE ARRANGEMENT.

Application filed July 2, 1923. Serial No. 648,907.

This invention relates to a new and improved power cultivator and more particularly to a hoe arrangement for such cultivators.

It is necessary with implements such as hoes operating upon the soil, that these implements be capable of adjustment in a vertical plane, not only to vary the depth of the cut or operation upon the soil, but also in order that they may clear the ground entirely when making turns or when traveling along the road. In a machine equipped with implements adapted to work upon opposite sides of a row of plants, it is also desirable that the different sets of implements be capable of both joint and independent vertical adjustment in order to take care of varying conditions.

It is an object of the present invention to provide a new and improved power hoe arrangement whereby the hoes are positively driven and are adapted for movement in a vertical plane to vary their height relative to the vehicle.

It is a further object to provide means of this character in which separate implement mechanisms carried by the vehicle may be raised or lowered independently or jointly as desired.

It is an additional object to provide such adjustable hoe arrangement with counterbalance means whereby the hoes may be adjusted without excessive labor and whereby they tend to remain in adjusted position.

It is also an object to provide mechanism of the character described in connection with shaft driven hoes.

Other and further objects will appear as the description proceeds.

We have illustrated a preferred embodiment of our invention in the accompanying drawings, in which:

Figure 1 is an elevation taken on line 1—1 of Figure 3 showing a cultivator provided with our improved hoe arrangement, with the hoes lowered.

Figure 2 is a view similar to Figure 1 but taken on line 2—2 of Figure 3 with the hoes raised; and

Figure 3 is a plan view of the machine.

The tractor comprises the engine 21 which is rigidly connected to the gear case 22. The gear case is provided with the horizontal protecting portions 23 and 24 to which

are connected the bevel gear housings 25 and 26. The wheel-drive housings 27 and 28 extend downwardly from the housings 25 and 26, respectively. These housings 27 and 28 carry the front wheel axles 29 and 30 upon which are the wheels 31 and 32.

The rear end of the gear case 22 is connected to the longitudinal truss 33 and the rear end of this truss is secured to the rear frame members 34 and 35 by means of clamps. The members 34 and 35 carry the vertically extending members 36 and 37 which latter have pivoted thereto the yokes 39 and 40. These yokes carry the rear axles supporting the rear wheels 41 and 42. The yokes 39 and 40 are connected by the cross tie members 43 and 44 which latter are adjustably connected as shown at 45.

The member 44 carries the lug 46 which engages the operating link 47, which is connected to a slide 48 carried by yoke 49. The yoke 49 is carried upon the rear end of the shaft 50. The slide 48, carried by yoke 49, is provided with stud 134 upon which is loosely fitted the lower end of the link 135. The upper end of the link 135 is fitted upon a pin 136 carried by the bifurcated end of lever 137. Both these connections are adapted to permit considerable play. The lever 137 is pivoted at 138 and is provided with the lock 139 co-operating with the toothed rack 140, as shown in Figure 1.

The forward end of the shaft 50 is provided with the arm 51 which is connected to link 52, the opposite end of which engages lug 53. Lug 53 is carried by the connecting member 54 which connects the steering knuckles 55 and 56 of the front wheels. The steering wheel 57 is carried by shaft 58, the rear portion of which is supported in bearing 59. The shaft 58 is connected by the universal joint 60 with the shaft section 61, which latter carries the worm 62 meshing with the gear 63. The gear 63 is carried on the vertical shaft 64, the lower end of which carries the steering arm 65. The steering arm 65 is connected by link 66 to the steering knuckle 56 of the right front wheel.

The shaft 70 is connected to the engine by any usual type of clutch and change speed gearing which forms no part of the present invention and need not be shown or described in detail. The shaft 70 carries the bevel gear 71 which meshes with a similar gear

keyed to the transverse shaft 86. The bevel-gears 88 are slidably carried by the shaft 86, being constrained by keys to rotate with the shaft. These gears 88 mesh with gears 90 carried by the hoe drive shafts 91 and 92. The hoe driving bevel-gear connections at each side of the shaft 86 are enclosed in housings 93 and 94, respectively.

The lower ends of the shafts 91 and 92 carry bevel-gears as indicated in broken lines in Figure 1 which shows gear 95 carried by shaft 91. These gears mesh with similar gears carried by short transverse shafts, each end of which is provided with a crank arm. As shown in Figure 1, the crank arm 97 engages link 98 which supports the hoe carrying frame 99 which carries hoes 100 and 101. The link 98 is pivoted in the frame 99 and the springs 140 and 141 are secured in the frame and engage opposite sides of the link so that the frame is yieldingly supported from the link, the springs cushioning relative movement and rebound in either direction.

The rod 120 is pivotally connected at one end to the hoe-carrying member 99. This rod 120 passes through the carrier member 121 which latter is pivotally supported upon the housing 122 which encloses the shaft 92.

A spring 123 is fitted upon the rod 120 between the member 121 and the hoe-carrying member 99. A second spring 124 is fitted upon the outer end of the rod and is retained in place by a nut 125 together with a washer.

It will be understood that the arrangement at the lower end of shaft 91 is similar to that just described.

The transverse supporting members 103 and 104 are carried by the central frame 33 and extend parallel with and adjacent to the shaft 86. The members 105 and 106 shown in Figure 3 are carried upon one end of these transverse members and similar members 107 and 108 are carried upon the opposite end of the members.

The members 105 and 106 receive trunnions formed upon the housing 94 concentric with shaft 86. The side member 110 of the housing 94 is provided with the ear 113 to which is pivotally connected the link 114. This link 114 is pivotally connected at its free end to the link 115, the upper end of which is pivotally connected to the ear 116 which is formed integrally with the member 105. The rod 117 has one end pivotally connected to the member 105 and its free end carries a washer and nut which retain the spring 118 in place upon the member. The pivot member 119 is carried by the member 117 and is urged by the spring 118 into engagement with a seat formed on the link 115.

The link 126 connects the housing 122 with the end of the bell crank lever 127. This lever 127 is pivoted upon shaft 128 and

is provided with a sliding lock 129 which cooperates with a toothed sector 130 fixedly secured to shaft 128. As shown in Figure 1, the opposite side of the machine is similarly equipped. The lever 131 is keyed to the shaft 128 and is provided with the lock member 132 which co-operates with a toothed rack 133 which latter is fixedly secured to the vehicle frame 33.

The bent supporting bar 134 is secured to the housing 122 and supports the plate 135 which is hung upon hinge 136. The bolt 137, secured to plate 135, passes through bar 134 and the spring 138 surrounding the bolt yieldingly resists swinging movement of the plate. The longitudinally extending guard plate 139 is supported from the housing 122.

In the operation of the steering mechanism, the front wheels are steered by rotating the hand wheel 57. This motion is transmitted through shafts 58 and 61 and through the vertical shaft 64 to the arm 65 and link 66. Through the connection established by the lug 53, link 52 and arm 51, the shaft 50 is rotated upon steering movement of the forward wheels. When the slide 48 is located in line with the axis of the shaft 50, substantially no movement is imparted to link 47 by rotation of the shaft.

If the slide 48 is raised by swinging downwardly the rear end of the lever 137, movement of the front wheels as shown in Figure 3 will cause the shaft 50 to be rotated in such manner as to draw the slide 48 to the right and consequently this movement through the link 47 and stud 46 swings the rear wheels in the same direction as the front wheels. The movement of the rear wheels is governed in amount by the distance which the slide 48 is raised above its neutral position. If the slide 48 is lowered by means of lever 137, the rear wheels are swung in the opposite direction to the front wheels.

The hoes 100 and 101 are driven by means of the crank arms 97 which latter are driven by means of the shaft 92 and cross shaft 86 with their co-operating gears. The rod 123 and its springs which cooperate with the sleeves 121 restrain the movement of the upper end of the hoe carrying frame 99. They cause the hoes to have an approximately elliptical movement. The springs 124 are also adapted to yield when the hoes strike a relatively hard or immovable substance and will thus prevent damage to the hoes or to the vehicle structure. The springs 123 cushion rebound after such yielding. The springs 140 and 141 cushion against vertically applied resistance or shocks.

The hoes are swung upwardly out of engagement with the ground or are adjusted to vary the depth of cut by means of the levers 127 and 131. The lever 131 serves to move the hoes upon both sides of the ma-

chine since this lever is keyed to the shaft 128 and the side levers 127 are constrained to move with the shaft by means of their connection to the shaft through the lug 129 and sector 130 which lug is keyed to the shaft.

The hoes upon either side of the machine may be controlled independently of those upon the other side by means of the corresponding lever 127. Each lever 127 rotates about shaft 128 which remains stationary as do the sectors 130 in this method of operation.

In raising or lowering the hoes, the shaft 92 and the entire hoe assembly rotate about the shaft 86. The trunnions 109 and 111 of the housing members rotate in the fixed members 105 and 106, the latter members being held against rotation by their support upon shafts 103 and 104. The upward movement of the hoes is assisted by the spring 118 which thrusts member 119 against link 115 and urges that link inwardly. The upper pivot point of the link 115 is fixed and movement of the link inwardly thrusts downwardly upon link 114 which link is connected to ear 113 carried by the moving housing. Similarly, when the hoes are lowered, the movement is eased by the resistance of the spring 118 which is compressed by the movement of the links.

As the hoes are raised, the two links approach a straight line and although the spring is expanded, its leverage is gradually increased and consequently the effective resulting force is substantially constant. In lowering the hoes the spring leverage is decreased as the spring is compressed. The force in either direction is so proportioned that the movement is accomplished by the application of but small force and the hoes tend to remain in adjusted position.

It will be understood that where the operation of one side of the machine has been described in connection with the hoe assemblies that the operation of the other side is identical.

We claim:

1. In combination with a cultivator, an implement carrying member pivotally mounted on the cultivator, and means connecting the member and cultivator to counterbalance the weight of the assembly when the latter is moved about said pivoted connection, said means comprising a pair of pivotally connected links, one end of the pair being connected to the cultivator and the other end to the assembly supporting member, and a spring thrusting against one of the links adjacent their pivoted connection, the thrust of the spring tending to straighten out the links and thereby swing the assembly carrying member to raise the assembly.

2. In combination with a power cultiva-

tor, a driven cross shaft, a downwardly extending shaft driven from the cross shaft, implements driven by the latter shaft, a housing for said latter shaft, the upper end of the housing being pivoted about the axis of the cross shaft, a lug upon the upper portion of said housing, links connecting the lug and a fixed portion of the cultivator, and a spring associated with the links, the spring being compressed by the links as the housing is swung downwardly.

3. In combination with a power cultivator, a driven cross shaft, a downwardly extending shaft driven from the cross shaft, implements driven by the latter shaft, a housing for said latter shaft, the upper end of the housing being pivoted about the axis of the cross shaft, a lug upon the upper portion of said housing, links connecting the lug and a fixed portion of the cultivator, and a spring thrusting against the links, the thrust of the spring assisting in straightening out the links as the housing is swung upwardly.

4. In combination with a power cultivator, a driven cross shaft, a downwardly extending shaft driven from the cross shaft, implements driven by the latter shaft, a housing for said latter shaft, the upper end of the housing being pivoted about the axis of the cross shaft, a lug upon the upper portion of said housing, a pair of pivotally connected links connecting the lug and a fixed portion of the cultivator, a rod pivotally connected to the cultivator, a bearing member engaging one of the links adjacent their pivoted connection, and a spring surrounding the rod and engaging the bearing member, the thrust of the spring resisting downward movement of the housing and assisting upward movement thereof.

5. In combination with a power cultivator, a driven cross shaft, a downwardly extending shaft driven from the cross shaft, implements driven by the latter shaft, a housing for said latter shaft, the upper end of the housing being pivoted about the axis of the cross shaft, a lug upon the upper portion of said housing, a pair of pivotally connected links connecting the lug and a fixed portion of the cultivator, a rod pivotally connected to the cultivator, a bearing member engaging one of the links adjacent their pivoted connection, a spring surrounding the rod and engaging the bearing member, the thrust of the spring resisting downward movement of the housing and assisting upward movement thereof, and a lever connected to the housing whereby the housing may be swung to raise or lower the implements.

Signed at Port Washington, Wisconsin, this 23rd day of May, 1923.
